UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

AUTOMATIC RIBBON-REVERSE.

1,385,548.

Specification of Letters Patent. Patented July 26, 1921.

Application filed March 10, 1919. Serial No. 281,739.

To all whom it may concern:

Be it known that I, OTTO A. HOKANSON, a citizen of the United States, and a resident of Woodstock, in the county of McHenry 5 and State of Illinois, have invented certain new and useful Improvements in Automatic Ribbon-Reverse, of which the following is a specification.

This invention has for its object the provision of mechanism of the class named which shall be of improved construction and operation.

The invention is exemplified in the combination and arrangement of parts shown in 15 the accompanying drawings and described in the following specification, and it is more particularly pointed out in the appended claims.

In the drawings—

20 Figure 1 is a vertical sectional view through a portion of a typewriter showing one embodiment of the present invention applied thereto.

25 Fig. 2 is a fragmentary detail of one feature of the invention.

Fig. 3 is a modification of the detail shown in Fig. 2.

Fig. 4 is a bottom plan view of the mechanism shown in Fig. 1.

30 Fig. 5 is a detail of one feature of the mechanism shown in Fig. 4.

Fig. 6 is a view similar to Fig. 4 showing a modification of the invention.

Fig. 7 is a vertical section on line 7—7 of

35 Fig. 6.

Fig. 8 is a vertical section on line 8—8 of Fig. 6.

Fig. 9 shows a detail.

In the drawings, the numeral 10 designates a portion of the top plate of a typewriter frame on which a ribbon spool casing 11 is mounted. The ribbon spool shaft 12 is journaled in the top plate 10 and is provided with a ratchet wheel 13 beneath the

45 plate by which the shaft is rotated. A ribbon spool 14 is held on the upper end of the shaft by means of a removable nut 15. Mounted to slide vertically in an axial opening in the shaft 12 is a rod 16 which is pro-

50 vided with a laterally bent portion 17 at its upper end projecting from the shaft 12 through a slot therein. A trip finger 18 is carried by a yoke 19 which is pivotally

mounted at 21 upon a collar 22 secured to the shaft 12. The trip finger 18 is provided with an opening through which the projection 17 on the rod 16 extends. As shown in Fig. 2, the pivot screw 21 carries a spring lever 23 provided with a flange 24 which projects laterally beneath the lower edge 55 of the yoke 19. A coil spring 25 surrounds the pivot screw 21 and has one end bent laterally to project into an opening 26 in the collar 22. The other end of the coil spring 25 projects into an opening 27 in the spring 60 lever 23. The lever 23 is provided with an arm 28 which bears against the lower face of the ribbon spool 14 so that the lever is held in the position shown in Fig. 1 by the downward pressure of the spool upon the arm 28 65 when the spool is held in place on the shaft 12 by the nut 15. When the nut 15 is released and the spool 14 is removed from the shaft 12, the spring 25 will rotate the lever 23 in a clockwise direction about the pivot 70 screw 21, as viewed in Fig. 1, causing the flange 24 to engage the yoke 19 and swing the trip finger 18 inwardly toward the upper end of the shaft 12. In this way the trip finger 18 is automatically swung into 75 position to permit a new spool, of ribbon to be placed upon the shaft 12. It is understood that the trip finger 18 projects through a slot 29 in the lower flange of the ribbon spool and normally lies within the core 30 80 of the ribbon spool about which the ribbon is wound. When a new spool is placed upon the ribbon spool holder, the lower flange of the spool will engage the arm 28 and force the spring lever 23 downwardly so that the trip finger 18 is free to fall into the position 85 shown in Fig. 1 as soon as the ribbon is unwound from the core 30 of the spool 14. The release of the trip finger 18 when the ribbon is unwound automatically reverses the 90 driving mechanism for the ribbon spools to rewind the ribbon upon the empty spool by mechanism to be described. It may be desirable, in some instances, to provide the pivot screw 21 with a separate collar, as 95 shown at 31 in Fig. 3, so that the coil spring 25 will not bind directly upon the pivot screw and tend to prevent free rotation of the parts upon the pivot.

The lower end of the rod 16 is provided 100 with a disk 32 having flanges 33 and 34

thereon which engage opposite sides of an enlarged end 35 on a lever 36 which is pivoted at 37 on a collar 38 carried by a screw 39 projecting downwardly from the lower face of the top plate 10. The end of the lever 36 opposite the enlargement 35 is provided with a cam 40 coöoperating with a cam roller 41 on a bell crank lever 42 pivoted at 43 to the lower face of the top plate 10.

10 The end of the lever 42 opposite the roller 41 is pivotally connected at 44 to a link 45 which has its opposite end pivoted, as shown in Fig. 5, to an arm 46 carried on an operating shaft 47 for driving the ribbon mechanism. The shaft 47 is oscillated about its axis in a manner well known in the art at each operation of a typewriter key. The shaft 47 is provided with a second arm 48 which carries an operating pawl 49 arranged to engage the notches on the ratchet wheel 13, as shown in Fig. 4. A holding dog 50 is pivotally mounted at 51 on the lower face of the top plate 10 and is provided with an arm 52 connected by a spring 53 with the operating pawl 49. It will be apparent that the spring 53 tends to draw the two pawls 49 and 50 into engagement with the ratchet wheel 13. The shaft 47 is shiftable longitudinally in its bearings in the top plate 10 and in the position shown in Fig. 4, the pawls 49 and 50 are thrown out of engagement with the ratchet wheel 13. A shifting lever 54 is provided with a pin 55 which projects into an opening in the periphery of the shaft 47 so that movement of the lever 54 will shift the shaft 47 longitudinally in its bearings. The lever 54 is rigidly connected to the upper end of the collar 38 which carries the lever 35. The lower end of the lever 54 is provided with a beveled point 57 which engages a roller 58 on the end of a bell crank 59 pivotally mounted at 60 on the plate 10. A spring 61 normally swings the pin 58 into engagement with the beveled end of the lever 54. It will be apparent that whenever the lever 54 is swung upon its pivot screw 39 so that the point of the lever passes the center of the roller 58, the spring 61 will cause the lever 54 to be swung to the opposite extreme of its arc of movement, thus preventing the lever from remaining in an intermediate position and insuring a complete shifting of the shaft 47 whenever the lever 54 is operated.

55 The mechanism connected with a single spool only is shown in the drawing, but it is understood that the other spool is provided with similar mechanism and that the shaft 47 is common to both spools. Whenever the ribbon becomes unwound from one of the spools so that the trip finger 18 is permitted to drop downwardly and outwardly, as shown in Fig. 1, the disk 32 on the lower end of the shaft 16 will be lowered and the lever 36 will be swung about its pivot 37 so that the cam member 40 will be swung upwardly into the path of the roller 41 on the lever 42. When this occurs the oscillation of the lever 42 will cause the roller 41 to engage the cam 40 as soon as one of the keys of the typewriter is struck and swing the lever 36 in a clockwise direction as viewed in Fig. 4. This, of course, will rotate the collar 38 and the trip lever 54 in a similar direction and bring the pointed end 57 of the lever 54 past the center of the pin 58 on the spring lever 59. The spring 61 will complete the movement of the lever 54 to shift the shaft 47 longitudinally in a downward direction, as viewed in Fig. 4. This will move the pawls 49 and 50 into engagement with the ratchet wheel 13 so that further oscillation of the shaft 47 will rotate the ratchet wheel 13 and cause the ribbon to be wound upon the spool. The movement of the shaft 47 at the same time, of course, will shift the corresponding pawls out of engagement with the opposite ribbon spool so that the ribbon is free to unwind from the opposite spool. As soon as the ribbon is rewound upon the spool, the trip finger 18 will be drawn inwardly and the rod 16 will be raised upwardly so that the cam member 40 will be moved downwardly out of the path of the roller 41. This, however, will not restore the shaft 47 to its original position for the reason that the shaft will be held in the position to which it was shifted by the pin 58 on the lever 59. The shaft will remain in this position until the opposite spool from that shown in the drawing is unwound at which time the mechanism controlled by that spool will return the shaft to its original position, thus again reversing the ribbon.

In the form of the invention shown in Figs. 6 to 9, inclusive, the holding pawl 65 is mounted on the pivot 66 and is provided with a pin 67 projecting through an opening in the operating pawl 68 and provided with a head 69 by which the operating pawl may be withdrawn from engagement with the ratchet wheel 13. The operating pawl 68 is connected at 70 with an arm 71 secured to a collar 72 mounted upon an oscillatory sleeve 73. The sleeve 73 is caused to oscillate whenever a key is struck, in the same manner as the oscillation of the shaft 47 in the form of the invention previously described. A shaft 74 extends through the axis of the sleeve 73 and is free to slide longitudinally within the sleeve. A lever 75 is provided with a pin 76 which connects the shaft 74 to the lever 75 in the same manner as the pin 55 in the form of the invention previously described. A bell crank 77 is provided with a roller 78 and a spring 79 to coöperate with the end of the lever 75, similar to the bell crank 59 in the previously described form of the invention.

The lever 75 is fixed to the upper end of a sleeve 80 pivotally mounted upon a bolt 81 which projects downwardly from the top plate 10. An arm 82 is formed integrally with the lever 75 and is provided with a roller 83 arranged in position to engage the end of a lever-arm 84 rigidly connected with the holding pawl 65 and extending on the opposite side of the pivot 66 from the holding pawl. It will be apparent that if the lever 75 is moved in a counter-clockwise direction upon its pivot 81, the roller 83 will engage the end of the lever 84 and move the pawl 65 out of engagement with the teeth of the ratchet wheel 13. When this occurs the head 69 on the pin 67 will draw the pawl 68 out of engagement also with the ratchet 13. At the same time the shaft 74 will be shifted longitudinally in the sleeve 73 and will operate mechanism similar to that shown in the drawings, but connected with the other ribbon spool to permit the pawls at the opposite end of the shaft 74 to be brought into engagement with the ratchet at that end and thus reverse the direction of rotation of ribbon spools. The pawl 65 is normally drawn toward the ratchet wheel 13 by a spring 85 connected with an arm 86 formed integrally with the pivotal bearing portion of the pawl 65. Whenever the roller 83 is moved away from the end of the lever 84, by movement of the shaft 74, the pawl 65 will be automatically drawn into engagement with the ratchet 13 by the spring 85. A spring 87 will also draw the pawl 68 into engagement with the ratchet wheel whenever such movement is permitted by the head 69 on the pin 67.

Connected at 88 to the arm 71 is a slide bar 89 having a slot 90 through which a screw 91 is passed, the screw being carried by a depending member 92 extending downwardly from the top plate 10. The end of the bar 89 carries an up-turned flange 93 in position to engage a roller 94 on the end of an arm 95 carried by a member 96 pivotally mounted at 97 on the sleeve 80. The member 96 has a second arm 98 provided with a laterally extended portion 99 which lies between the flanges 33 and 34 of the disk 32. It will be understood that when the ribbon is unwound from the ribbon spool and the disk 32 is dropped downwardly the roller 94 will be lowered into the path of movement of the flange 93 on the slide bar 89, but when the ribbon is wound upon the spool and the disk 32 is lifted, the member 96 will be raised about its pivot 97 and the roller 94 will be lifted above the path of movement of the upturned flange 93.

The parts in Fig. 6 are shown in the position they occupy when the ribbon is being wound on the spool. The parts will continue in the positions shown until the ribbon 65 is unwound from the opposite spool at which

time the shaft 74 will be shifted downwardly, as viewed in Fig. 6 to rotate the lever 75 in a counter-clockwise direction which will cause the roller 83 to engage the lever 84 and move the pawls 65 and 68 out of engagement with the ratchet wheel 13. The same rotation of the lever 75 will shift the roller 94 to the right, as viewed in Fig. 6, so that it will be in position to be engaged by the flange 93 when the ribbon has become unwound from the ribbon spool, and the roller 94 is dropped downwardly into the path of oscillation of the flange 93. It will be understood that the bar 89 and flange 93 are oscillated each time one of the keys of the typewriter is struck and as soon as the ribbon becomes unwound from the ribbon spool, the roller 94 will be lowered into the path of movement of the flange 93 and the next operation of a type key will shift the roller 94 and the mechanism controlled thereby into the position shown in Fig. 6 and throw the operating pawls 65 and 68 immediately into engagement with the ratchet wheel 13 so that the ribbon begins at once to be rewound upon the ribbon spool. In this way complete reversal of the ribbon is effected at a single stroke of a typewriter key after the ribbon has become unwound from one of the spools. This avoids the necessity of the ribbon remaining stationary and receiving the impact of the type on one spot for a number of strokes of the typewriter keys as is the case where a number of strokes of the typewriter is required for reversing the ribbon feed mechanism. The same quick reversal of the ribbon feed is accomplished by the form of the invention shown in Figs. 1 to 5, inclusive.

I claim:

1. The combination with a ribbon spool, of mechanism for rotating said spool, means for reversing said rotating mechanism to cause reversal of the direction of movement of a ribbon wound upon said spool, means for actuating said reversing means, said actuating means being arranged to move at each printing operation, and means controlled by the ribbon on said spool for moving said reversing means into operative relation with said actuating means to cause a reversal of the movement of said ribbon.

2. The combination with a ribbon spool, of a drive shaft therefor arranged to oscillate about its axis, means for shifting said shaft longitudinally of its axis for reversing the rotation of said spool, means actuated by the oscillation of said shaft for actuating the shifting means for said shaft, and a device controlled by the ribbon on said spool for effecting an operative connection between said shaft-shifting means and the actuating means therefor.

3. In combination, a ribbon spool, an oscillatory shaft for operating said spool,

105

110

115

120

125

130

- means for shifting said shaft to reverse the direction of rotation of said spool, and a device controlled by the ribbon upon said spool for connecting said shifting means with said shaft so that the oscillation of said shaft will operate said shifting means. 70
4. In combination, a ribbon spool, an oscillatory shaft for rotating said spool, a movable member actuated by the oscillation 75 of said shaft, means for shifting said shaft longitudinally to reverse the direction of rotation of said spool, and a device controlled by the ribbon upon said spool and shifted into and out of position to be engaged by said movable member, said device being connected with the shifting means for said shaft to produce a longitudinal movement of said shaft when said device is engaged by said movable member. 80
- 10 5. In combination, a ribbon spool, an oscillatory shaft for rotating said spool, means for shifting said shaft longitudinally to reverse the direction of rotation of said spool, a device operated by the oscillation of said 85 shaft for actuating said shifting means, a pivoted lever movable into and out of position for connecting said shifting means with its actuating device, and means controlled by the ribbon on said spool for moving said lever to produce a shifting of said shaft when the ribbon is unwound from said spool. 90
- 15 6. An automatic ribbon reverse comprising ribbon actuating mechanism, a control lever arranged to move about an axis in one direction to produce a reversal of said actuating mechanism and pivoted to move about an axis in another direction into and out of operative position, and means engaging 95 said control lever to shift said lever into and out of operative position, said shifting means being arranged to permit movement of said lever to perform a reversing operation of said actuating means while continuing in engagement with said lever. 100
- 20 7. In combination, a ribbon spool, an oscillatory shaft for actuating said spool, a pivoted arm for shifting said shaft longitudinally to reverse the direction of rotation of said spool, a lever for actuating said arm, means actuated by the oscillation of said shaft for moving said lever, and a device controlled by the ribbon on said spool for shifting said lever into and out of position to be engaged by said lever-moving 105 means to cause said lever to actuate said arm and produce a reversal of the rotation of said spool. 110
- 25 8. In combination, a ribbon spool, mechanism for rotating said spool, means for reversing said spool-rotating mechanism, a lever for controlling said reversing means, and a member controlled by the ribbon on said spool for engaging said lever to permit 115 free movement of said lever in one direction while remaining in engagement therewith but arranged to move said lever in another direction to shift said lever into and out of position to cause reversal of said spool-actuating mechanism. 120
- 30 9. In combination, a ribbon spool, a movable device controlled by the ribbon on said spool and arranged to be shifted when the ribbon is unwound from said spool, mechanism for rotating said spool, a movable device for reversing said spool rotating mechanism, means for actuating said last-named movable device at each operation of a typewriter key, and means controlled by the first-named movable device for connecting 125 said spool-operating mechanism with said key-actuated movable device to cause a reversal of said rotating mechanism at a single operation of said key-actuated movable device subsequent to the shifting of said ribbon control movable device. 130
- 35 10. In a typewriter, the combination with ribbon feeding mechanism, of means having its complete operation limited to a single stroke of said typewriter for reversing said ribbon feeding mechanism, and means for controlling said ribbon reversing means to cause the same to be operated to reverse said ribbon feeding mechanism while the ribbon remains slack. 95
- 40 11. In a typewriter, the combination with ribbon feeding mechanism, of means controlled by the ribbon fed by said mechanism while said ribbon remains slack for reversing said mechanism, said reversing 100 means being actuated under the control of said ribbon and through its complete range of movement during a single operation of a typewriter key to effect a complete reversal of said ribbon feeding mechanism. 105
- 45 12. In a typewriter, a ribbon spool, means for rotating said spool to wind a ribbon thereon, means for controlling said spool rotating means to cause reversal of the direction of rotation of said spool, means for 110 actuating said controlling means through its complete range of movement during a single operation of said typewriter to completely effect a reversal of said spool rotating means, and means for causing said actuating means to operate upon said controlling means when the ribbon is unwound from said spool and while it remains slack. 115
- 50 13. In a typewriter, ribbon feeding mechanism, means for reversing said ribbon feeding mechanism, means for controlling said reversing means arranged to be actuated when the ribbon on said typewriter reaches a predetermined relation with its feeding mechanism, and means for actuating said 120 ribbon reversing mechanism through its complete range of movement during a single stroke of said typewriter subsequent to the actuation of said controlling means. 125
- 55 14. In combination, a ribbon spool, means 130

for rotating said spool to wind a ribbon thereon, key actuated mechanism for reversing said rotating means, and means controlled by the ribbon for rendering said key actuated reversing mechanism operative when the ribbon has been unwound from said spool and while the ribbon remains

slack to positively cause complete reversal of said rotating means at a single operation of said key actuated reversing mechanism. 10

In testimony whereof I have signed my name to this specification on this 1st day of March, A. D. 1919.

OTTO A. HOKANSON.
